UNITED STATES PATENT OFFICE.

PHILIP C. WENTWORTH, OF PROVIDENCE, RHODE ISLAND.

RING TRAVELER.

Application filed January 17, 1924. Serial No. 686,854.

To all whom it may concern:

Be it known that I, PHILIP C. WENTWORTH, a citizen of the United States, residing at Providence, county of Providence, State of Rhode Island, have invented certain new and useful Improvements in Ring Travelers, of which the following is a specification.

In my previous Letters Patent No. 1,10 461,059, July 10, 1923, I disclosed and discussed a new traveler and method of making the same, the invention having particular reference to the production of a greater hardness in the terminal horns of the traveler as distinguished from the intermediate or so-called bow portion.

My present improvement relates to a new form of traveler in accordance with this invention and one which has great adaptability and great importance.

In travelers for certain kinds of work the particular form shown in my previous patent is sometimes unavailable particularly for very fine work but the variable temper is none the less very important and desirable. The object of my present invention is a traveler having the characteristic hardness or temper of my former invention but capable of production even in very small sizes.

I have found that it is possible by variably reducing the width of the bow portion of the traveler blank to obtain in a finished traveler an article of different shape but of the same general characteristics as that heretofore described by me. I am aware that it has been proposed to make a traveler having enlarged and thickened horns by which somewhat the general appearance of my present traveler was presented but it was not contemplated as far as I am aware in that or in any other traveler to provide it with a differential temper.

As illustrative of my invention I have shown in the accompanying drawings a simple form of high efficiency and one well adapted to meet a range of requirement heretofore difficult to fill. Throughout the specification and drawings reference characters are employed after the usual manner, and in the drawings:

Fig. 1 is a side elevation of a traveler in accordance with my invention.

Fig. 2 is a plan view of the same, and 55
Fig. 3 a central section on the line 3—3,
Fig. 1.

Such a traveler comprises a bow portion B and terminal horns H and is preferably produced from a strip of stock of uniform 60 width and thickness and having uniform low carbon content as in accordance with my previous patent. The strip of stock which forms the flat blank from which my traveler is made is provided on each side of its bow portion with a long smoothly rounded symmetrical scallop S by which the natural width of the metal blank may be narrowed to any desired amount.

The amount of metal therefore in the region of the bow diminishes from the area of the horns variably towards the center of the traveler. From the blank so formed the traveler itself is built up after the usual manner and then treated to increase its carbon content. The travelers may be packed in layers in any suitable carbonizing material such as bone black and heated in a furnace for some six or seven hours to assure as complete an absorption of carbon by the metal of the traveler as is possible throughout the entire traveler. The travelers are then withdrawn and quenched and at that stage are extremely hard but correspondingly brittle. The travelers are then subjected to a slow heat by which the temper is withdrawn and in this action the bows being of lesser diameter respond more rapidly to the treatment. Under the tempering heat the carbon begins to recombine more quickly in the bows and by suitably timing the tempering a maximum degree of hardness may be retained in the horns while the carbon in the bows may be considerably recombined so that upon quenching they will be found to have a maximum hardness at the horns and a very considerable resiliency at the bows.

For the purposes of this application I shall discuss my invention in its relation to the ring traveler of the "horseshoe" type, comprising terminal horns and a connecting bow. It is to be understood, however, that such treatment is purely illustrative and in no way limiting, and that the term "ring traveler" is to be construed in its broadest sense as referring to any traveler whether for ring spinning or twisting, which travels about a ring, and so construed to cover either

the "horseshoe" or the vertical type of traveler.

What I therefore claim and desire to secure by Letters Patent is:

5. A ring traveler comprising a bow and terminal horns of uniform thickness throughout, but diminishing in width from the horns towards the center of the bow 10 symmetrically with reference to the longitudinal median line of the traveler.
15. 2. A ring traveler comprising a bow and terminal horns of uniform thickness throughout, but diminishing in width from the horns towards the center of the bow 15 symmetrically with reference to the longitudinal median line of the traveler, the edges of the bow in said diminished areas being smoothly rounded.
20. 3. A ring traveler comprising a bow and terminal horns, said horns of uniform width and thickness throughout, and said bow of uniform thickness but diminishing in width from the horns towards the center of the bow 25 symmetrically with reference to the longitudinal median line of the traveler.
25. 4. A ring traveler comprising a bow and terminal horns, said horns of uniform width and thickness throughout, and said bow of the same thickness as the horns and being 30 provided on its marginal edges with symmetrically disposed scallops.

5. A ring traveler comprising a bow and terminal horns, said horns of uniform width and thickness throughout, and said bow of the same thickness as the horns and being 35 provided on its marginal edges with symmetrically disposed scallops, said scallops extending continuously from the horns towards the center of the bow.

6. A hardened and tempered one piece 40 ring traveler comprising a relatively soft spring tempered bow and relatively harder terminal horns, said horns of uniform width and thickness throughout, and said bow of uniform thickness but diminishing in width 45 from the horns towards the center of the bow.

7. A hardened and tempered ring traveler comprising a bow and terminal horns of uniform thickness throughout but diminishing in width from the horns towards the center of the bow, the tempering effect being greater in the bow than in the horns, and the horns having greater hardness than said 50 bow.

In testimony whereof I affix my signature in presence of two witnesses.

PHILIP C. WENTWORTH.
